UNITED STATES PATENT OFFICE.

JAMES A. COFFEE, OF LAWRENCEVILLE, NEW JERSEY.

SUPPORTING APPARATUS FOR FURNACE HOES OR POKER-BARS.

1,171,504.

Specification of Letters Patent.

Patented Feb. 15, 1916.

Application filed September 17, 1915. Serial No. 512,257.

To all whom it may concern:

Be it known that I, JAMES A. COFFEE, a citizen of the United States, residing at Lawrenceville, in the county of Mercer and State of New Jersey, have invented certain new and useful Improvements in Supporting Apparatus for Furnace Hoes or Poker-Bars, of which the following is a specification.

10 My invention relates to apparatus for supporting a hoe or poker-bar, employed in connection with a furnace, for cleaning it, breaking up clinkers or the like.

An important object of the invention is 15 to provide apparatus of the above mentioned character, which will support the hoe or poker-bar and permit of its free unrestricted movement, with the least resistance, and which will not interfere with the 20 opening and closing of the furnace door or doors.

Other objects and advantages of the invention will be apparent during the course of the following description.

25 In the accompanying drawings forming a part of this specification and in which like numerals are employed to designate like parts throughout the same, Figure 1 is a side elevation of apparatus embodying my invention, showing the same applied to a furnace, Fig. 2 is a plan view of the same, Fig. 3 is a side elevation of a slightly different form of apparatus, Fig. 4 is an end elevation of the same, and, Fig. 5 is a detail 30 section through a roller embodied in each form of the invention.

Each form of the invention comprises a tubular roller 10, which may be formed of a section of pipe. This roller is carried by 40 a shaft 11 and bearing elements or rolls 12 are interposed between the same. These bearing elements are held in place by caps 13 having screw-threaded engagement with the ends of the shaft 11. Connected with 45 the ends of the shaft 11 are cranks 14, having lateral extensions 15.

In Figs. 1 and 2, the numeral 16 designates a furnace having a pair of openings 17, normally covered by horizontally swinging doors 18, having hinges embodying 50 knuckles 19 and 20, rigidly secured to the doors and the furnace respectively. Rigidly attached to the furnace between the openings 17 is a bracket 21, as shown. As shown

in Figs. 1 and 2, one door 18 is open and 55 the roller 10 is arranged in front of the opening 17, with the extensions 15 of the cranks 14 contacting with the knuckle 19 and the bracket 21. The cranks 14 are thus pivotally supported or suspended, and 60 are detachable from their supports. The bracket 21 is so arranged that it will support either crank 14 when the roller 10 is placed adjacent either opening 17.

In Figs. 3 and 4, a furnace is shown having 65 a door 22, covering the door opening. The extensions 15 of the crank 14 are pivoted within journals or bearings 23, rigidly attached to the furnace. When the roller 10 is not in use it assumes the lower position 70 out of the way of the door 22, which may be conveniently opened or closed. To use the roller, the door is opened and the roller moved to the upper position, indicated in Fig. 4. A pivoted pawl 24 is 75 arranged adjacent each crank 14, and is adapted to be swung upwardly for engagement beneath a lug or tooth 25, carried by the crank 14.

In the operation of each form of apparatus, when the roller 10 is in the active position, the hoe or poker-bar is placed thereon and supported thereby. The longitudinal movement of the poker-bar causes the rotation of the roller and the poker-bar may 80 be conveniently shifted to any desired angular position with relation thereto.

It is to be understood that the forms of my invention herewith shown and described are to be taken as preferred examples of 85 the same, and that various changes in the shape, size, and arrangement of parts may be resorted to without departing from the spirit of the invention or the scope of the subjoined claims.

Having thus described the invention, I 90 claim:

1. The combination with an approximately horizontal shaft arranged near the door opening of a furnace and extending 100 for substantially the length of the door opening and provided at its ends with cranks, means for connecting the cranks with the furnace casing, and a roller having an opening to receive the shaft and extending for substantially the entire length 105 of the door opening and having a smooth periphery.

2. The combination with an approximately horizontal shaft arranged near the door opening of a furnace and having cranks, of means for pivotally connecting the cranks with the furnace casing to swing upwardly and outwardly to its operative position, means to lock the cranks in the elevated position, and a roller carried by

the shaft and extending throughout the greater portion of its length.

In testimony whereof I affix my signature in presence of two witnesses.

JAMES A. COFFEE.
